UNITED STATES PATENT OFFICE.

JOHN C. BECKFIELD, OF PITTSBURG, PENNSYLVANIA.

GAS-BURNER FOR FURNACES.

No. 800,708.

Specification of Letters Patent.

Patented Oct. 3, 1905.

Application filed December 27, 1900. Serial No. 41,231.

To all whom it may concern:

Be it known that I, JOHN C. BECKFIELD, a citizen of the United States, and a resident of Pittsburg, in the county of Allegheny and 5 State of Pennsylvania, have invented a certain new and useful Improvement in Gas-Burners for Furnaces, of which the following is a specification.

My invention relates to fuel-gas burners for 10 furnaces; and my object is to produce a burner having a series of burners connected to a common source of gas-supply, the burners being provided with independent means to mix the air and gas and so disposed with relation to a 15 shield above the same as to throw the flame outward therefrom and cause the air to ascend up through the space between the burners and the shield to the rear of the flame to prevent as much as possible the passage of 20 cold air up the walls of the furnace; and to these purposes my invention consists in the novel construction and arrangement of parts hereinafter set forth and described, reference being had to the accompanying drawings, 25 forming part hereof, in which—

Figure 1 indicates a plan view of my improved gas-burner for furnaces. Fig. 2 is an elevation of the same. Fig. 3 is a section taken on the line 3 3 of Fig. 1. 30 Referring to said drawings, 1 is an annular base or support, the upper edge of which is provided with an outwardly-projecting flange *a*, which serves as a shield or guide to project the flame from the burners toward the 35 walls of the furnace, and an inwardly-inclined top *b*, which is bolted or otherwise suitably secured to the gas reservoir or chamber 2, both having lugs *c*, which are provided with bolt-orifices for the reception of the bolts *d* 40 to admit of this. The said annular support is preferably formed in two parts or sections, the divisional line of which is section-line 3 3 of Fig. 1, to enable the same to be quickly and readily placed in the furnace through the 45 door thereof. The said reservoir 2, on the lower side or bottom thereof, is provided with a centrally-disposed boss *e*, which is screw-threaded for the reception of the upper correspondingly-threaded end of the gas-supply 50 pipe 3. 4 4 are series of radially-disposed gas-discharge pipes constituting burners, the inner ends of which are screw-threaded and connected to and communicate with the interior of the gas reservoir or chamber 2 and are 55 each provided with an orifice *f*, slightly in advance of the point at which said pipes are

connected with the gas-reservoir, whereby air is admitted to each of said burners and caused to mix with the gas prior to its emission through the small perforations *g*, formed 60 around the periphery of the flared or bell-shaped outer end of the said gas-discharge pipes, at which point it is ignited. The said annular base or support has formed therein a number of V-shaped openings *h*, extending 65 from the lower edge thereof to a point slightly above or on the same horizontal plane with the top of said gas reservoir or chamber. The gas-discharge pipes project in said openings, the flared outer end of said pipes terminating 70 approximately on a vertical plane with the periphery or outer edge of the shield of the circular base, forming a contracted space above and to the rear of the burners, the shield forming a guide or deflecting plate, which 75 causes the flames from the burners to be projected toward and against the walls of the furnace and thereby limit the volume of air or prevent the passage of the same upward against the walls of the furnace between said 80 walls and the burners and at the same time causing the air to pass to the rear of the flame below the shield. The space between the burners forms legs *j*, upon which said annular support rests when placed within the furnace. 85

The said burner when arranged for use is placed in such wise in the furnace that the edges of the shield and the outer ends of the burners are in close proximity with the walls *k* of the furnace, forming a very narrow or 90 contracted space between the burner and the said walls. A ring *m*, preferably of asbestos board, upon which said support rests, is arranged upon the grate *n* adjacent to the walls and in close contact therewith, forming a barrier 95 to the passage of air up through the space between the face of the burners and the walls and causes the air admitted below the burner to pass to the rear of and above the burners, and thus largely minimizing the volume of 100 cold air that may possibly come in contact with the walls of the furnace.

What I claim, and desire to secure by Letters Patent, is—

1. In a fuel-gas appliance for furnaces, the combination of a furnace, a gas-chamber therein, a gas-supply pipe connected thereto, a series of independent horizontally-disposed burners communicating therewith, the said chamber having a horizontally-disposed lip or flange constituting a continuous projection above said burners and terminating a short 105 110

distance from the walls of said furnace and forming a contracted opening above the burners between said flange and said burners and between the walls and flange or lip, whereby 5 the air is caused to travel to the rear of said burners and between said burners and said flange.

2. A fuel-gas burner comprising an annular support, the top or upper edge having a flange 10 and having a number of openings in the sides thereof, a circular centrally-disposed gas-reservoir connected to said annular support provided with a gas-supply pipe, a series of radially-disposed gas-discharge pipes connected 15 with said gas-reservoir the outer ends of which terminate in a semispherical chamber the periphery of which is provided with numerous minute perforations, and means to supply air to each of said gas-discharge pipes 20 independently, substantially as set forth.

3. In a fuel-gas appliance for furnaces, the combination of a furnace, a gas-chamber therein, a gas-supply pipe connected thereto, a series of independent horizontally-disposed 25 burners communicating therewith, provided with independent mixers, and a support connected to said chamber, the upper edge of which is provided with a lip or flange terminating a short distance from the walls of said

furnace and constituting a continuous projection above said burners and forming a contracted opening above the burners between said flange and the burners and between the walls of said furnace and flange, whereby the air is caused to travel to the rear of said burners through the space or opening above said burners. 30 35

4. A fuel-gas burner comprising a centrally-disposed gas reservoir or chamber, a series of gas-discharge pipes connected to and communicating with said reservoir, an annular base or support for said gas reservoir and burners, the upper edge of which is provided with a flange or shield projecting outwardly above the burners, means to admit air to each of 40 said gas-discharge pipes, means to supply gas to said reservoir, in combination with a ring arranged below and supporting said annular base and in close proximity with the walls of the furnace, substantially as set forth. 45 50

In testimony whereof I have hereunto set my signature in the presence of two subscribing witnesses.

JOHN C. BECKFIELD.
